UNITED STATES PATENT OFFICE.

JOHN W. BUICKEROOD, OF BOUND BROOK, NEW JERSEY.

MARCEL WAVER.

1,042,886.

Specification of Letters Patent. Patented Oct. 29, 1912.

Application filed March 30, 1912. Serial No. 687,312.

To all whom it may concern:

Be it known that I, JOHN W. BUICKEROOD, a citizen of the United States, and a resident of Boundbrook, in the county of 5 Somerset and State of New Jersey, have invented a new and Improved Marcel Waver, of which the following is a full, clear, and exact description.

This invention relates to toilet articles 10 and especially to devices used in dressing the hair, the special object of the invention being to provide a waver of a cheap and simple nature and which may be used rapidly and with the highest degree of satisfaction.

A further object of the invention is to provide a device which will prove the least injurious to the user's hair.

The foregoing and other objects are attained in a preferred embodiment of the invention by means of the device hereinafter fully described and claimed and illustrated in the accompanying drawings, in which—

Figure 1 is a perspective view of a waver 25 with a strand of hair secured thereto; Fig. 2 is a side elevation of the same, partly broken away, with the parts in normal unapplied position; Fig. 3 is an end elevation of the same.

This Marcel waver comprises a tubular body 10 of a length and diameter suitable for the purpose, such dimensions being variable according to the desires of the different users. The body 10 is made of some 35 suitable strong and cheap material, such as absorbent paper, in order that it may absorb the oil or moisture which may be used in dressing the hair. Preferably also the tubular body is made slightly tapering, as 40 shown.

At 11 is indicated a light elongated spring of any suitable material, that shown being

of flat spring metal. One end 12 of said spring is bent upon itself so as to bear against and be held in place by the opposite 45 walls of the body 10 when the spring is thrust into one end of said body. From said end 12 the spring extends upward and is thence bent backward toward the smaller 50 end of the body, the spring in its normal position being spaced from the body 10 as shown substantially in Fig. 2.

In using the waver as thus described, a strand of hair is first passed beneath the spring 11 and the body, the first coil of the 55 hair being held between the spring and the body, and the subsequent coils of hair will be wound around on the outside of both the body and the spring. The small ends of the hair strand will be secured in any simple 60 convenient manner as, for instance, by being drawn into one or more cross slits 10^a of the body.

Having thus described my invention, what I claim as new and desire to secure by Letters Patent is:

The herein described Marcel waver comprising a tubular body portion and a flat spring, said spring having one end bent upon itself and adapted to frictionally engage with the opposite sides of the inner wall of said body portion near one end thereof and thence extending outwardly through said end of the body portion and thence bent over and toward the opposite 75 end of the body portion.

In testimony whereof I have signed my name to this specification in the presence of two subscribing witnesses.

JOHN W. BUICKEROOD.
